UNITED STATES PATENT OFFICE.

PETER KESHNER AND HENRY LAUX, OF CARLYLE, ILLINOIS.

RAILWAY TIE AND CLAMP.

SPECIFICATION forming part of Letters Patent No. 568,619, dated September 29, 1896.

Application filed May 15, 1896. Serial No. 591,612. (No model.)

To all whom it may concern:

Be it known that we, PETER KESHNER and HENRY LAUX, of Carlyle, in the county of Clinton and State of Illinois, have invented 5 certain new and useful Improvements in Railway Ties and Clamps, of which the following is a full, clear, and exact description.

This invention relates to ties and clamps for the rails of railways, and the object is to 10 provide a tie and clamp of simplicity, durability, and comparative cheapness, and in which the clamp is interchangeable or adapted for use on either side of a rail.

We will describe a tie and clamp embodying our invention, and then point out the 15 novel features in the appended claims.

Reference is to be had to the accompanying drawings, forming a part of this specification, in which similar characters of reference indicate 20 corresponding parts in all the figures.

Figure 1 is a perspective view of a tie and clamp embodying our invention. Fig. 2 is a plan view thereof. Fig. 3 is a section on the line 3 3 of Fig. 2, and Fig. 4 is a perspective 25 view of a clamp.

Referring to the drawings, 1 designates the metal tie of semicylindrical form and having outwardly-extending base-flanges 2 at its 30 sides and which form a solid foundation and prevent the tie from sinking into the road-bed. The tie is preferably formed of thin plate-steel and it is open at its ends, so that a filling 3, of dirt or other material, may be introduced, and thus make a practically solid 35 tie.

The rail-clamp comprises a body portion 4, curved on its inner surface to fit snugly against the tie, and provided on its upper side with a jaw 5, adapted to engage over the 40 base-flange of a rail and to engage its end with a portion of the rail-web, as plainly shown in the drawings. The clamp has an outwardly-extended base-flange 6, adapted to bear upon the flange 2 of the tie and also 45 to engage over and against the edge of said tie-flange.

In use a clamp is placed at each side of the tie and engaging with opposite sides of the rail, and the two clamps of a pair are secured 50 rigidly in place by means of bolts 7, which pass through the body portions of the clamps and transversely through the tie, and prefer-

ably the clamps will be provided with recesses to receive the heads of the bolts, so as to prevent turning when the nuts are screwed on. 55 The holes through the clamps may be slightly elongated to allow of adjustment with relation to the width of a rail-flange.

The clamps are extended in such manner as to engage a portion of their upper sides 60 against the bottom of a rail, and thus the clamps are designed to support the rail vertically as well as to secure it laterally. The upper side of the tie is transversely depressed to form a level seat for the rail, as indicated 65 at 8, and this level portion 8 is on a plane with the top portions of the clamps with which the rail engages.

It will be seen that the clamps and bolts will prevent any lateral spreading of a tie, 70 and that as the clamps are all of like construction they can be used at either side of a rail.

If desired, holes may be made through the flanges 6 of the clamps, so that they can be 75 bolted to wood or metal on elevated roads or structures or bridges; and, further, it is obvious that by a slight modification in form the clamps may be adapted for use with square wooden ties. 80

Having thus described our invention, we claim as new and desire to secure by Letters Patent—

1. The combination with a railway-tie, curved in cross-section and having its flanges 85 of a rail-clamp having its inner surface conformed to the tie and having a jaw to engage a rail, and also having a flange for engaging the top and edge of the tie-flange, substantially as specified. 90

2. The combination with a semicylindrical metal tie, having base-flanges and flat or depressed portions, of rail-clamps having a body portion conformed to the curve of the tie and having flanges to engage the tops and edges of the tie-flanges, substantially as specified. 95

3. The combination with a semicylindrical plate-metal tie having base-flanges, of rail-clamps adapted to fit against the sides of the tie and also having a top portion to engage against the under side of a rail, jaws on the clamps to engage over the base-flange of the rail and against the rail-web, flanges on the 100

clamps to engage over the flanges of the tie-flanges, and the fastening-bolts, substantially as specified.

4. A railway-tie having an outwardly-extending base-flange and a rail-clamp secured to one side of the tie and having at its upper portion a jaw capable of engaging the base-flange of the rail and at its lower portion an

outwardly-extending flange passing over and bearing down upon the flange of the tie, substantially as described.

PETER KESHNER.
HENRY LAUX.
